THERMAL INSULATING ARTICLE AND
ASSEMBLY

Frank P. Pusio, Manville, N. J., assignor to Johns-Manville Corporation, New York, N. Y., a corporation of New York

Application February 3, 1937, Serial No. 123,806

2 Claims. (Cl. 154—44)

This invention relates to a thermal insulating article and assembly thereof upon an object of curvilinear exterior surface.

The cost of shipping thermal insulation shaped at the place of manufacture to fit around a furnace or tank, for example, is excessive. Also, the expense of manufacturing such an article may be relatively large.

It is an object of the present invention to provide insulation for an object such as a furnace, tank, or the like, of curved exterior surfaces, that may be made and shipped in flat form and then fitted around the object, with the provision of efficient insulation.

In the preferred embodiment, the invention comprises thick sheet insulation provided with closely spaced deep scorings such as cuts or saw kerfs adapting the sheet to conform to a curvilinear surface. The invention comprises also the means herein described for minimizing flow of heat through the said scorings.

The invention is illustrated in the attached drawing and will be described in connection here-with, for the purpose of exemplification.

Fig. 1 is a perspective view of an assembly made in accordance with the present invention.

Fig. 2 is a plan view of the scored insulating sheet.

Fig. 3 is a sectional view of the insulation.

Fig. 4 is an enlarged sectional view of an insulated curvilinear surface.

In Fig. 1 there is shown a furnace or tank 11 with the insulation over the end thereof omitted, to show better the fitting of the improved insulating article 12.

This insulating sheet is thick, say about three-quarters of an inch or more in thickness, and is provided with closely spaced deep scorings 13 which extend generally parallel to each other, across the sheet, that is, from end to end or side to side thereof, and divide the sheet into narrow sections. These sections extend generally parallel to each other and are flexibly or hingedly united by the outer layers or portions 14 of the insulation which are not cut through by the scorings.

In applying such a scored sheet to the outside of the object of curved surface, the insulation is applied with the scored surface inward and with the depths of the scorings extending in the directions of the radii of curvature of the exterior surface of the object. Thus, when the object is cylindrical, the sections defined between the adjacent scorings extend lengthwise

of the cylinder and the scorings extend approximately as projections of radii.

In such an assembly, as illustrated in part on a larger scale in Fig. 4, the sections contact at their mid-portions 15 with the insulated surface 5 and are spaced therefrom at the edges of the sections, where adjacent sections preferably abut, practically to close the entrances to the scorings.

Furthermore, the scorings are advantageously filled, in part at least, with a compressible thermal insulating material so that, as the insulation is fitted around the curvilinear surface, the thermal insulating filling of the scorings serves to restrict air circulation within the scoring and thus to minimize transfer of heat therethrough.

As illustrated in Fig. 2, the scorings may be spaced differently in different parts of the sheet, to promote conformance of the sheet over a surface of various radii of curvature. Thus, the sheet may have the scorings close together in the part to be conformed to sharply curving surfaces, far apart for slightly curving surfaces, or absent entirely in areas of the sheet that are to be fitted over flat portions of an object, as, for instance, over the flat sides of the object of approximately elliptical shape of cross section shown in Fig. 1.

In making the improved insulating article, the following method has been found to be convenient.

There is first formed a sheet of composited layers of corrugated and plane asbestos paper, preferably in alternating relationship to each other, the adjacent sheets being adhered together by sodium silicate or other conventional adhesive. Thus, there may be built up a plied composite of the thickness of an inch or so. This composite is then laid flat and scored, as, for instance, with a series of gang saws spaced from each other, to cut the scorings (in this case saw kerfs) at the desired distances apart, and so adjusted as to cut from one face inwardly, almost but not quite through the composite. In this way, there is left the hinge portion 14 which extends between the adjacent sections of the scored insulation and permits flexing while holding together all of the said sections. The sections are individually substantially rigid. The paper of which the hinge portion 14 is part constitutes a continuous backing member for the insulating material.

The scoring by the saws gives a fibrous compressible mass 17 of loose asbestos which remains largely in the scorings and is not removed therefrom after the scoring is completed.

If desired, other filling may be introduced into the scorings, as, for example, shredded wool felt, granulated 85% magnesia insulation, or a plastic insulating material adapted to remain in the scorings without uniting the sections rigidly.

The spacings of the scorings and their dimensions are determined by the conditions under which the article is to be used, as indicated above by the curvature of the object to be insulated.

10 Thus, I have used, in an insulating article of compositized spaced sheets of asbestos paper one inch thick, scorings that are one to three inches apart and of width each of about one-eighth inch or more. These score marks suitably extend 15 through all but two of the outer layers of the asbestos paper, the total number of layers being about four of corrugated and five of plane paper to the inch of thickness of the sheet, and the plane paper preferably being exposed on both 20 faces of the insulation.

The corrugations may be exposed, in alternate layers of the corrugated paper, the scoring as described being adequate to impart the necessary flexibility to the sheet as a whole.

25 Other types of construction may be used, as, for instance, in a composite of desired thickness, sheets of paper containing therein particles of sponge or provided otherwise with irregularities of surface serving to space adjacent sheets from 30 each other over the major portion of their areas. Another material that may be used is indented or irregularly surfaced wool felt paper compositized with itself to give the desired thickness of the insulating article.

35 It will be understood that the details given are

for the purpose of illustration and not restriction. Variations within the spirit of the invention are intended to be included in the scope of the appended claims.

What I claim is:

1. Thermal insulation for application to an object of curved surface, said insulation comprising a relatively thick sheet having closely spaced, deep scorings extending inwardly from a face of the sheet which is to lie adjacent said curved surface and extending across the sheet in approximate parallelism to define narrow sections therebetween, each of said scorings containing a compressible mass of loose fibrous material whereby upon application of the sheet to 15 the object of curved surface the scorings are substantially closed at the said face of the sheet and the mass of fibrous material is compressed to provide an insulating filling for the scorings.

2. In combination an object of curved surface 20 and a thermal insulating cover therefor, said insulating cover comprising a relatively thick sheet of originally plane surface having closely spaced, deep scorings extending inwardly from the face of the sheet adjacent said curved surface and 25 extending across the sheet in approximate parallelism and defining narrow sections therebetween, said sections contacting with the curved surface, said scorings being substantially closed at said face of the sheet and each containing 30 a compressed mass of fibrous material whereby the continuity of the insulation is preserved and transfer of heat at the scorings is minimized.
